FRICTION TOP CAN

Leslie W. Hills, San Francisco, Calif., assignor to
 Hills Bros. Coffee, Inc., San Francisco, Calif.,
 a corporation of California

Application June 29, 1942, Serial No. 448,931

11 Claims. (Cl. 220—42)

1

This invention relates to prangible solder sealed tops for cans or containers, and is more particularly directed to the formation of a prangible hermetical seal as a closure for a container end and which end may have two sealing connections including a prangible soldered primary seal for the maintenance of the contents of the can or container, and a secondary seal operable when the primary seal is broken to prevent rapid deterioration of the product contained within the can.

In the preservation of food products, particularly of the character susceptible to deterioration after opening as, for example, coffee, spices, paint, and other similar products which are generally retained in the can and used therefrom, there has long been sought some form of container which would enable the same to be sealed as it is packed, either under partial vacuum pressure, or the like, and which container would also provide a means which would permit its easy opening and at the same time provide a relatively tight cover providing a secondary seal which would permit the cover to be removed and replaced after the breaking of the primary seal.

In such a container it is essential that the secondary seal permit of easy removal and replacing of the cover or closure member while providing a relatively tight seal so that the contents of the can or container may be used therefrom easily and as desired.

I have found that I am able to form a primary seal for such a container which is easily broken by a prying action by forming a solder seal of limited width and which limited solder seal will withstand high internal pressures and high internal vacuums alternately making the same particularly applicable for use as a container for products such as coffee and the like which are packed under high vacuum and then develop a relatively high internal pressure.

It is therefore an object of my invention to provide a sanitary can or container having a cover member providing primary and secondary seals where the primary seal is of a permanent, enduring, and air-tight character operable to maintain the contents within the can and of the order necessary to retain a vacuum or pressure, the secondary seal being of such character after destruction of the primary seal to protect the contents of the sanitary can.

Another object of my invention is to provide a friction top lid including an annular ring having mounted therein a friction top and between which friction top and annular ring there is provided a permanent seal which may be easily broken by a simple prying operation.

Another object of this invention is to provide a can end providing an hermetical seal which may be easily broken by a prying action and which is capable of withstanding alternate pressures over

2

the range of the vacuum of the order of 30 inches of mercury and 20 pounds per square inch above atmospheric pressure.

Another object of my invention is to provide a top for a sanitary can which includes a primary and a secondary seal between the top or lid and an annular ring forming one end portion of such can, and which seals are of such character as to permit their being broken without mutilating or destroying the top or the annular ring.

Another object of this invention is to provide a friction top lid for a sanitary can having a solder seal of such confined area as to form an effective seal and yet which may be easily broken by a prying action, without requiring the use of a special form of prying tool.

Another object of this invention is to provide the top and the annular ring of the end member of a sanitary can with annular flange means for the purpose of confining the area of the primary seal formed between said top and annular ring.

Another object of this invention lies in the formation of the primary and secondary seals in such spaced relation as to avoid adherence of the cooperating surfaces of the secondary seal during the soldering of said primary seal.

Another object of this invention resides in the formation of the primary and secondary seals in such manner as to confine the solder in the locality of said primary seal and to prevent the solder from flowing into said secondary seal.

Other objects and advantages of this invention it is believed will be apparent from the following detailed description of a preferred embodiment thereof as illustrated in the accompanying drawings.

In the drawings:

Figure 1 is a perspective view of a sanitary can incorporating a friction top embodying my invention.

Figure 2 is a fragmental sectional view taken substantially on the line 2—2 of Figure 1.

Figure 3 is a view similar to Figure 2 of a modified form of structure embodying my invention.

Figure 4 is an enlarged fragmental sectional view in which the relative thicknesses are exaggerated for the purpose of illustration.

Figure 5 is a view similar to Figure 4 but being particularly applicable to the form of construction illustrated in Figure 3.

In accordance with my invention, a sanitary can or other container 1 of any suitable or desirable construction adapted to contain food or other material is provided with an end assembly 2.

As illustrated in Figures 1 and 2, the end is a fabricated structure formed of sheet metal and consisting of an annular ring or wall part 3 and a friction top or cover part 4. The end assembly 2 is formed in any suitable or desirable way as is

well understood in the art to enable the same to be rolled or crimped to the body of the container 1 as, for example, illustrated at 5. The particular manner of rolling or crimping the end 2 to the body 1 is commonly practiced in the art and forms no part of my invention.

The end assembly 2 is fabricated so as to provide between the annular ring 3 and the friction top 4 a primary seal 6 and a secondary seal 7. The entire end for the sanitary container 1 is preferably fabricated before the end is assembled or secured to the container 1. The annular ring 3 is formed at its outer edge to permit the formation of the double seam 5 and at its inner edge is provided with a vertically extending annular flange 8 providing the cylindrical surface 9, which defines the peripheral edge of an opening affording access to the interior of the container 1.

Intermediate the inner and outer edges of the ring, the ring is formed in such manner as to provide a confining area member in the form of a ridge or flange 10 for the formation of the friction top primary seal 6. The formation of the ring 3, as illustrated in Figure 1, to provide a solder confining area member or flange 10 for the formation of the primary seal 6, not only reinforces the ring, but also provides a more restricted and perfect sealing area at the apex of such flange. The raising of this sealing section also provides that the top 4 when secured in position to form the primary seal will be raised at its outer edge 11 away from the annular ring 3 sufficient to permit the easy insertion of a tool or instrument between the annular ring 3 and the flange 11 for prying the top 4 away from the annular ring 3 to break the primary seal.

The friction top 4 is formed in any suitable or desirable manner to provide a complementary cylindrical surface 12 adapted to cooperate with the cylindrical surface 9 to form a friction seal. These two complementary cylindrical surfaces form the secondary seal. The friction top 4, outwardly from the cylindrical surface 9, is provided with the annular flange 11, which is preferably formed in such manner as to provide an annular confining area primary sealing section 13 overlying the primary seal area provided by the apex of the flange 10 of the annular ring 3. This confining area is preferably formed in such manner as to reinforce the flange 11 at the point of formation of the primary seal so that a more perfect sealing surface will be had. The formation of the confining section 13 in the top 4 also serves to straighten out any waves or other variations present in the material forming the top 4, producing a soldering area plane limited by the width of the flange 10 which cooperates with the section 13.

As illustrated in Figure 1, this reinforcing of the annular flange 11 is provided by deforming the flange in any suitable or desirable manner to form a channel 14 into which the complementary vertical flange providing the sealing section 10 of the annular ring 3 extends.

It will be evident that the construction described for the top or cover part 4 including the lateral offsetting which forms the cylindrical surface 12, serves to stiffen the cover against lateral bending. Likewise the offsetting which provides the flange 8 and ridge-like portion 10 serves to stiffen the ring or wall part 3.

I prefer to form the primary seal by producing a readily frangible solder connection between the surfaces 10 and 13 by first tinning one or both of the two mating surfaces in any suitable

or desirable manner and then under the combined influence of heat and pressure, fuse the tinned surfaces together. For this purpose any ordinary or low temperature melting solders may be employed. In any event, the solder or primary seal is spaced from the surfaces 9 and 12 forming the secondary or friction seal 7 and is prevented from flowing into said secondary seal. By thus forming the primary seal, a pressure-tight seal is maintained over the limited areas 10 and 13, which is easily broken by the prying action obtained from inserting a suitable tool such as the handle end of a common table spoon under the outwardly extending section of the flange 11 and prying upwardly. This action will break the primary seal and continued prying will force apart the secondary friction seal formed between the cylindrical surfaces 9 and 12. Thus, the container may be opened and when opened the desired quantity of material within the container may be removed and used as desired. The friction top 4 may then be replaced, reestablishing the secondary seal which will reduce to a minimum deterioration of the product contained within the container 1.

The primary seal embodying my invention I have found must be of limited character in order to permit the seal to be broken easily by a simple prying action as by inserting the end of a spoon or other blunt instrument under the edge 11 and prying upwardly over the rim of the container. A satisfactory form of such seal I have found is where the width of the radial or transverse cross-sectional dimension of the annular solder seal is about four times, or less, than the thickness of the sheet metal can stock of which the top 4 is formed. In practice I prefer to employ an annular solder seal which is about twice the thickness of the said stock, or for use in a one-pound coffee can, in the neighborhood of $\frac{1}{8}$ of an inch in width. On tests of such a primary seal, I have found that the same is able to withstand the highest vacuum commercially attainable as utilized in the vacuum packing of products such as coffee, and will likewise withstand the pressure which develops in such a container which may develop to the extent of approximately 20 pounds per square inch above atmospheric pressure.

It is apparent that the primary seal used for this purpose must be able to withstand this alternate pressure condition to maintain the contents hermetically sealed under high vacuum and have sufficient strength to prevent any possibility of the cover 4 being blown away from the ring 2 when the relatively high pressure develops within the can.

While I have hereinabove specified the solder seal width as being related to the thickness of the sheet metal stock used in forming the top 4, it will be apparent that such stock may vary. This stock ordinarily employed in one-pound coffee cans has a thickness of about .010". There is, however, a definite relationship between the thickness of the stock and the radial width of the solder seal having a definite relation to the ability to pry the top 4 away from the ring 2. As the stock decreases in thickness, it will be necessary to reduce the width of the solder seal because under such circumstances the top 4 as formed of such stock would have less rigidity or resistance to deformation under a prying action. As the thickness of the stock increased, the thickness of the solder seal may likewise be increased without danger of the friction top becoming destructively deformed or mutilated, under a prying

action. It is desirable to have a seal which will, however, open under a very slight prying action as long as that seal is effective to maintain the alternating pressure conditions as hereinabove specified.

In the second modification of my invention, as illustrated in Figure 3, similar parts are indicated by similar numerals with the addition of an exponent *a* thereto.

In this modification the annular ring *3a* is formed substantially in the same manner as described in connection with the modification of my invention in Figures 1 and 2 with the exception that the primary seal flange or ridge *10a* is formed with its sealing surface curved as illustrated at *15a*. In this modification, the secondary seal *1a* is illustrated as being formed in the same manner as in the first modification considered. The primary seal *6a* is, however, formed also by forming the friction top *4a* with a downwardly depending flange or ridge *16a* to provide a curved sealing area *13a* immediately over the curved sealing area *15a* of the annular ring *3a*.

In this modification the material forming the peripheral annular flange *11a* is doubled up on itself as at *17a* to reinforce the annular flange and the cover *4a* at the section adjacent the primary seal.

It will also be apparent from the foregoing description that one of the features of my invention is the forming of the primary seal *6* over a confined area as by flanging one or both of the parts of the assembly forming the primary seal to enable an accurate and reliable control of the width of the seal formed.

It is, of course, apparent that in the forming of the primary seal where solder is utilized the parts may be treated with a suitable flux prior to the sealing operation and it is also apparent that the cylindrical surfaces forming the secondary seal may be suitably treated to prevent the same from sticking together during the formation of the primary seal. These surfaces forming the friction seal may be effectively protected against sticking together during the formation of the primary seal by lithographing one or both of the cooperating surfaces forming the secondary friction seal.

It will be apparent also that the can top and end may be made of any suitable material which, when properly treated, may be joined together by soldering.

Referring particularly to Figures 4 and 5, I have shown the solder seals as hereinabove set forth enlarged for the purpose of illustration, Figure 4 being the seal of the first modification of Figure 2, while Figure 5 is the cylindrical seal and modification illustrated in Figure 3. In Figure 4 the width of the limited end area formed by the flange or ridge *10* is of the order of twice the thickness of the sheet metal stock and the width of the solder seal is limited accordingly. In Figure 5 the width of the limited end area of flange *10a* is of the order of four times the thickness of the sheet metal.

In these illustrations it will be observed that the solder seal "S" is limited by the area of the flange or flanges of the metal top and ring which cooperate in substantial contact. The end of the flange may thus be said to be a "limiter" of the width of the solder seal that may form the hermetical connection between the cover and ring.

Having fully described my invention, it is to be understood that I do not wish to be limited to

the details herein set forth, but my invention is of the full scope of the appended claims.

I claim:

1. A container having a metallic member provided with an opening; a pricable top of a given thickness serving as a closure for said opening, said container portion having a raised ridge extending completely around said opening, said pricable top having a depending similar ridge disposed inwardly of its peripheral edge and in confronting relation to said first-mentioned ridge; and a readily frangible, circumferentially continuous solder connection between the apexes of said ridges providing an hermetic seal between said container portion and pricable top, said frangible connection being of a radial width of not more than about four times the thickness of the top material, said ridges spacing the edge of said pricable top from said container portion so that said edge can serve as a prying lip.
2. In a container construction wherein a sheet metal wall part of the container is provided with an opening for access into the interior of the container, a cover part formed of sheet metal and relatively rigid in resisting lateral bending, one of said parts being provided with a ridge-like circularly contoured offset which presents an end area to the other part of limited radial width, a continuous frangible solder seal between said end area and the other part and forming a hermetic seal for said opening, and means carried by the cover to enable prying of the same in a direction away from the wall part, said solder seal being a narrow and continuous line of solder of uniform width which is frangible throughout its length upon application of prying forces insufficient to cause substantial mutilation of the cover part.
3. In a container construction wherein a sheet metal wall part of the container is provided with an opening for access into the interior of the container, a cover part formed of sheet metal, said cover part being provided with a ridge-like circularly contoured offset which presents an end area to the other part of limited radial width, a continuous frangible seal formed between said end area and the other part and forming a hermetic seal for said opening, and means carried by the cover to enable prying of the same in a direction away from the wall part, such seal being a narrow and continuous line of bonding material of uniform width which is frangible throughout its length upon application of prying forces insufficient to cause substantial mutilation of the cover part.
4. In a container construction wherein a sheet metal wall part of the container is provided with an opening for access into the interior of the container, a cover part formed of sheet metal, circularly contoured offsets formed on both the cover part and on the wall part, said offsets serving to stiffen said parts against lateral bending, one of said offsets being formed ridge-like to present an end area to the other offset which is of limited radial width, a continuous frangible seal between said end area and the other offset and forming a hermetic seal for said opening, and means carried by the cover to enable prying of the same in a direction away from the wall part, said seal being a narrow and continuous line of bonding material of uniform width which is frangible throughout its length upon application of prying forces to the cover insufficient to cause substantial mutilation of either the cover or wall parts.
5. In a container construction wherein a sheet

metal wall part of the container is provided with an opening for access into the interior of the container, a cover part formed of sheet metal stiffened by lateral offsetting whereby it is relatively rigid in resisting lateral bending, the wall part of the container being provided with lateral offsetting whereby it is relatively rigid in resisting bending, one of said parts being provided with a ridge-like circularly contoured offset which presents an end area to the other part of limited radial width, a continuous frangible solder seal between said end area and the other part and forming a hermetic seal for said opening, and means carried by the cover to enable prying of the same in a direction away from the wall part, said solder seal being a narrow and continuous line of solder which is of a uniform width of not more than about four times the thickness of the sheet metal and is frangible throughout its length upon application of prying forces to the cover insufficient to cause substantial mutilation of the same.

6. In a container construction wherein a sheet metal wall part of the container is provided with an opening for access into the interior of the container, a cover part formed of sheet metal having an annular offset proportioned to have frictional engagement with the opening, said offset portion serving to stiffen the cover part against lateral bending, one of said parts being formed to provide another annular offset forming a ridge and presenting an end area to the other part which is of limited radial width, said area being spaced from said frictional engagement, a frangible solder seal between said area and the other part and forming a hermetic seal for said opening, and means carried by the cover to enable prying of the same in a direction away from the wall part, said solder seal being confined to a uniform width by the limited end area of said ridge to provide a seal which is frangible throughout its length upon application of prying forces to the cover insufficient to cause substantial mutilation of the same, whereby said cover is frictionally engageable with said opening after breaking of said solder seal.

7. In a container construction wherein a sheet metal wall part of the container is provided with an opening for access into the interior of the container, a cover part formed of sheet metal provided with a circularly contoured offset serving to stiffen the same against lateral bending, the wall part being provided with a circularly contoured offset forming the periphery of the opening and with which the offset portion of the cover is adapted to frictionally engage, another circularly contoured ridge-like offset formed on one of the parts and presenting a relatively narrow circular end area to the other part, a frangible solder seal between said area and the other part and forming a hermetic seal about the opening, and means carried by the cover to enable prying of the same in a direction away from the cover, said solder seal being a narrow and continuous line of solder of uniform width not greater than about four times the thickness of the sheet metal and which is frangible throughout its length upon application of prying forces insufficient to cause substantial mutilation of the cover part.

8. In a container construction, a wall part formed of relatively bendable sheet metal having an opening for access into the interior of the container and provided with annular configurations about the opening to render said part relatively rigid, said configurations including a ridge-

5 like annular offset providing an end area having an effective width of not more than about four times the thickness of the sheet metal, a cover part likewise formed of relatively bendable sheet metal, said cover part being configurated annularly to provide a relatively true annular planar sealing surface and to render the cover relatively rigid against deformation when pried from the wall part, said cover being provided with means 10 serving to enable prying of the cover part in a direction away from the wall part of the container, and a hermetic solder seal between the end area of said ridge-like offset and said planar sealing surface of the cover part and forming a hermetic seal between said parts, said seal being limited in radial width by the width of the end area of said ridge to be readily frangible upon application of prying forces insufficient to deform the cover and wall parts.

20 9. In a container construction wherein a sheet metal wall part of the container is provided with an opening for access into the interior of the container, a cover part formed of sheet metal stiffened by lateral offsetting to resist lateral bending, a ridge-like circularly contoured offset formed on one of said parts and surrounding the opening, said last named offset presenting a limited end face area to the other part which has a width in a radial direction of the order of substantially twice the thickness of the sheet metal, a continuous frangible solder seal formed between said end face area and the other part and forming a hermetic seal for said opening, and means carried by the cover to enable prying of the same in a direction away from the wall part, said solder seal being frangible throughout its length upon application of prying forces insufficient to cause substantial mutilation of the cover part.

30 10. In a container construction wherein a sheet metal wall part of the container is provided with an opening for access into the interior of the container, a cover part having an annular offset portion serving to stiffen the same against lateral bending, the wall part having an offset about the opening adapted to be frictionally engaged by the offset of the cover part, a ridge-like circularly contoured offset formed on one of the parts and surrounding the opening, said last-named offset presenting a limited end face area to the other part which has a width in a radial direction of the order of not more than four times the thickness of the sheet metal, said end area being spaced from said frictional engagement, a continuous frangible connection between the end area and the adjacent area of the other part and forming a hermetic seal about the opening, the cover part having an edge portion spaced from the adjacent portion of the wall part by said ridge-like offset and forming means whereby the cover can be pried to break the entire length of the frangible connection and to remove the cover part from frictional engagement with the wall part without substantial mutilation of either cover or wall parts.

35 11. In a container construction wherein a sheet metal wall part of the container is provided with an opening for access into the interior of the container and a friction sealing surface surrounding the opening, a cover part formed of sheet metal and relatively rigid in resisting lateral bending, said cover part having a friction sealing surface for engaging said first named sealing surface, one of said parts being provided with a ridge-like circularly contoured offset which presents in solderable proximity to the other part

an end area of limited radial width, a continuous frangible solder seal between said end area and the other part and forming a hermetic seal for said opening, said seal being spaced from said friction sealing surface, and a flange carried by the cover to enable prying of the same in a direction away from the wall part, said solder seal being a narrow and continuous line of solder of uniform width which is frangible throughout its length upon application of prying forces insufficient to cause substantial mutilation of the cover part, at least one of said friction sealing surfaces being lithographed to prevent sticking during formation of a solder seal.
